UNITED STATES PATENT OFFICE.

THOMAS B. DWYER, OF LEWELLEN, NEBRASKA.

DESIGN FOR A HOG-HOLDER.

50,614.

Specification for Design.

Patented Apr. 17, 1917.

Application filed December 30, 1916. Serial No. 139,949. Term of patent 14 years.

To all whom it may concern:

Be it known that I, THOMAS B. DWYER, a citizen of the United States, residing at Lewellen, in the county of Garden and State of Nebraska, have invented a new, original, and ornamental Design for Hog-Holders, of which the following is a specification, reference being had to the accompanying drawing, forming part thereof.

The figure is a plan view of a hog holder, showing my new design.

I claim:

The ornamental design for a hog holder, as shown.

THOMAS B. DWYER.

Witnesses:

B. C. DELATOURE,
JNO. O. ROSS.
